DAVID P. DAVIS, OF NEW YORK, N. Y.

Letters Patent No. 71,718, dated December 3, 1867.

IMPROVED BELT-LACING DEVICE.

The Schedule referred to in these Letters Patent and making part of the same.

TO ALL WHOM IT MAY CONCERN:

Be it known that I, DAVID P. DAVIS, of the city, county, and State of New York, have invented a new and improved Lacing for Belts; and I do hereby declare that the following is a full, clear, and exact description thereof, which will enable those skilled in the art to make and use the same, reference being had to the accompanying drawings, forming part of this specification.

The present invention relates to an improved lacing, more especially intended for machine-belts and bands, and the lacing embraced herein is composed of two parts, of similar construction, with each part formed of a cross-bar having a series of arms, made of a hook-shape at their outer ends, so that the parts can be interlocked together, the hooks of one part with the cross-bar of the other, and thus if, by their arms, they are passed through suitable slits or openings made at the proper points in the belt, at or near its ends, the two ends of the belt will thereby be secured or fastened together, and in such a manner as to bring the strain upon the lacing through the thickness of the belt, in lieu of in the direction of its length and that of the slits through which the arms to the fastener pass. In the accompanying plate of drawings my improvements in lacings for belts are illustrated—

Figure 1 being a plan or top view of a lacing made according thereto, and on a belt; and

Figure 2 a section taken in the plane of the line $z z$, fig. 1.

Similar letters of reference indicate corresponding parts.

A, in the drawings, represents the two parts to my improved lacing, similarly constructed, and each made with a cross-bar, B, having a series of arms, C, of equal length, for each part, that, at their outer ends, are terminated with a hook, D, which, when the two parts of the lacing are put together, interlock or engage with the cross-bar of the opposite or other part, as shown in the drawings, consequently fastening the two parts together, and, if applied to the ends of a belt through suitable slits or openings thereof, interlocking or lacing such ends together.

I claim as new, and desire to secure by Letters Patent—

The two-part lacing A, for belts, etc., each similarly constructed, substantially as described.

DAVID P. DAVIS.
